(57) **CLAIM**

The ornamental design for a glove, as shown and described.

DESCRIPTION

FIG. 1 is a front view of a glove, showing my new design;

FIG. 2 is a rear view thereof;

FIG. 3 is a left-side view thereof;

FIG. 4 is a right-side view thereof;

FIG. 5 is a top view thereof;

FIG. 6 is a bottom view thereof; and,

FIG. 7 is a front plan view thereof, wherein a thumb is folded flat toward a pinky finger.

The short dash and long dash broken lines on the drawings depict portions of the glove that form no part of the claimed design.
